SCALE BEARING

William N. Gilbert, Hudson Heights, N. J., assignor, by mesne assignments, to International Business Machines Corporation, New York, N. Y., a corporation of New York

Application July 23, 1930, Serial No. 470,053

10 Claims. (Cl. 308—2)

This case relates to the pivot constructions of weighing scales.

The object of the invention is to provide novel means for securing pivots in their scale elements.

Another object is to provide novel means for finely adjusting pivots in their bearings.

Various other objects and advantages of my invention will be obvious from the following particular description of one form of mechanism embodying the invention or from an inspection of the accompanying drawing; and the invention also constitutes certain new and novel features of construction and combination of parts herein-after set forth and claimed.

15 In the drawings:

Fig. 1 is a top view of the bifurcated end of the lever with the bearings in place.

Fig. 2 is a side view of Fig. 1, partly in section.

Fig. 3 is a section along line 3—3 of Fig. 2.

20 Fig. 4 is a detail of an adjustment plate used for adjusting the angle of the knife edge.

Fig. 5 is a detail of the projecting end of the knife edge pivot.

Fig. 6 is a side view of a lever end of a different form than in Fig. 1 with the pivot assemblies in place.

Fig. 7 is a section on line 7—7 of Fig. 8 and Fig. 8 is a detail of the pivot construction with the parts in section.

30 Referring first to Figs. 6 to 8, the terminal portion 10 of the scale member 11 is formed with a round bore to receive the round end 12 of a pivot element 13. The round end 12 is provided with a V-shaped peripheral groove 14 adapted to receive steel balls 15. Threaded into a bore 16 of the portion 10 is a screw 17 having a conically pointed end 18 for wedging the balls 15 apart into contact with the walls of bore 16 (see Fig. 7) and at the same time wedging the balls down into

40 the groove 14 of the pivot end 12. In this manner, the pivot 13 is fixed against both rotation and endwise movement relative to the portion 10.

The outer flat face of the round portion 12 of the pivot is provided with a notch 20 for receiving a spanner tool or the like to rotate and thereby 45 adjust the pivot. After adjustment, the screw 17 is moved down into the bore to clamp the pivot against movement. A thrust plate 21 is provided to resist endwise movement of the V-groove bearing block 22 resting on the pivot 13.

In Figs. 1 to 5 is shown the bifurcated end 25 of a lever 26. Pivot 27 is locked at each end by the means described in Figs. 6 to 8. Instead of using a screw such as 17, however, the modification in 55 Figs. 1 to 5 is provided with a headed screw 28

between which and the edge of the lever furcation is held a spring washer 29 for resisting movement of the screw after it has been set and a U-shaped thrust member 30 for resisting endwise movement of the V-groove bearing block 31. 80

The knife edge pivot 32 is held at one end by the same means as the pivot 27. At the other end, the lever furcation carries a U-shaped member 33, the inner leg of which engages the top of the pivot 32 and resists end thrust of the bearing member 31 (see Fig. 3). The outer leg 34 is provided with a notch 35 for receiving the projection 36 (see Fig. 5) of the pivot end. Passing through the top of the U-shaped member 33 is a pair of spaced screws 37 threaded into the lever furcation. The member 33 is clamped to the lever furcation by these screws, downward movement of the member being limited by engagement of both legs with the pivot 32. When it is desired to rotatively adjust the pivot 32 the ball locking means for the pivot on the right side of the pivot (as viewed in Fig. 3) is released and the screws 37 moved relatively to tilt the member 33 and through engagement of slot 35 thereof with projection 36 rotate the pivot 32. Thereafter the ball lock is again tightened on the right hand end of the pivot thereby preventing further adjustment thereof. 75

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims. 85 90

I claim:

1. A device comprising a pivot having a circumferential peripheral open groove, a member having a hole for rotatively adjustably receiving the pivot, said member also having a bore extending angularly to the hole and opening into the hole, a pair of balls partly located in the bore and partly seated in the groove, and a wedge member adjustably carried in said bore and adapted to simultaneously wedge the balls apart into contact with the walls of the bore and force them towards the pivot and into contact with the walls of the groove to thereby clamp the pivot and holding member together against rotative and longitudinal movement in any rotatively adjusted position of the pivot in the holding member. 95 100 105 110

2. A device comprising a pivot, a holding member rotatably supporting the pivot, an adjustable element separately carried and secured to the holding member and engaging the pivot to adjust it relative to the holding member, means apart from said element for locking the pivot to the holding member after adjustment, said pivot having a projection on its outer end and said element having a slot coacting with said projection to lock the pivot and element together. 10
3. A device comprising a scale pivot structure including a linear bearing portion for engaging a similar bearing portion, a coacting scale pivot, said structure also including a part having a round portion provided with a concentric concave groove, a scale member having a round opening rotatively adjustably receiving said round portion and provided with a circular bore having a threaded portion, the bore extending angularly to said opening and said groove, a pair of round elements located in said bore and rotatably engaging the opposite walls thereof and the adjacent portions of the groove, and a screw threaded into the bore and having a wedge end for spreading the round elements apart towards opposite walls of said base into locking engagement with the walls of the bore and for simultaneously moving them towards the groove to lock against and thereby prevent relative longitudinal and rotative movement of the scale member and the pivot structure. 20
4. A device comprising a pivot element, a scale member having an opening for rotatably receiving the element, a device adapted to be mounted on the outside of said member after the pivot element is in place, said element having a non-circular portion extending outside the member, the device having a non-circular portion interlocking with the similar portion of the element, and means for adjusting the device to rotatably shift the pivot relative to the member. 30
5. A device comprising a pivot, a member for rotatably supporting said pivot, a rigid device carried by said member and having an extension disposed transversely to the pivot axis and provided with means for engaging the pivot, a bearing element mounted on said pivot, the device having another extension angular to the pivot axis for engaging one end of said bearing element to serve as an end thrust plate, and means for securing the device to the member against removal, the securing means being adapted to adjust the device for rotatably shifting the pivot relative to the member. 40
6. A device comprising a pivot, a scale member having an opening for rotatably receiving the pivot, the pivot having a non-circular portion extending outside the scale member, a bearing element supported by the pivot, and a U-shaped plate straddling the scale member having one leg provided with a non-circular portion for receiving the similar portion of said pivot, the other leg of said plate serving as a thrust plate to resist end thrust of the bearing element, and screws for securing the base of the U-shaped plate to the scale member and adapted to adjust the U-shaped plate to rotatively shift the pivot relative to the member. 50
7. In a scale, a lever having an arm provided with a round hole and angularly thereto a bore communicating with the hole, a knife edge extending laterally and exteriorly of the lever arm for rocking cooperation with a V-bearing block and having at the side thereof a round trunnion rotatively adjustably seated in said hole, rotative adjustment of the trunnion moving the knife edge angularly to vary its moment arm on the lever, a member adjustable along said bore and having a wedge end facing the trunnion, and an element interposed between the wedge end, the wall of the bore, and the trunnion surface closing the inner end of the bore and upon adjustment of the member along said bore forced by the wedge end towards and into wedging engagement with the wall of the bore and the aforesaid trunnion surface to thereby fix the knife edge against rotation relative to the lever and correspondingly fix the moment arm of the knife edge. 80
8. In a scale, a lever having an arm provided with a round hole and angularly thereto a bore communicating with the hole, a knife edge extending laterally and exteriorly of the lever arm for rocking cooperation with a V-bearing block and having at the side thereof a round trunnion rotatively adjustably seated in said hole, rotative adjustment of the trunnion moving the knife edge angularly to vary its moment arm on the lever, a member adjustable along said bore and having a wedge end facing the trunnion, and a round element rotatably interposed between the wedge end, the wall of the bore, and the trunnion surface closing the inner end of the bore and upon adjustment of the member along said bore forced by the wedge end towards and into wedging engagement with the wall of the bore and the aforesaid trunnion surface to thereby fix the knife edge against rotation relative to the lever and correspondingly fix the moment arm of the knife edge. 85
9. In a scale, a lever provided with a round hole and angularly thereto a threaded bore communicating at its inner end with said hole, a knife edge extending laterally and exteriorly of the lever side for rocking engagement with a coacting V-bearing and having at the side thereof a round trunnion rotatively adjustably seated in said hole, rotative adjustment of the trunnion moving the knife edge angularly to vary its moment arm on the lever, a screw adjustable along the threaded bore and having a wedge end facing the trunnion, and a pair of round elements rotatably engaged with and interposed between the wedge end, the wall of the bore, and the surface of the trunnion closing the bore and upon adjustment of the screw forced apart by the wedge end towards and into wedging coaction with the walls of the bore and the aforesaid trunnion surface to thereby fix the knife edge against rotation relative to the lever and to correspondingly fix the moment arm of the knife edge. 90
10. In a scale, a lever provided with a round hole and angularly thereto a threaded bore communicating at its inner end with said hole, a knife edge extending laterally and exteriorly of the lever side for rocking engagement with a coacting V-bearing and having at the side thereof a round trunnion rotatively adjustably seated in said hole, rotative adjustment of the trunnion moving the knife edge angularly to vary its moment arm on the lever, a member adjustable along said bore and having a wedge end facing the trunnion, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 95
11. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 100
12. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 105
13. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 110
14. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 115
15. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 120
16. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 125
17. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 130
18. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 135
19. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 140
20. In a scale, a lever having a round hole and angularly thereto a bore communicating with the hole, a knife edge extending laterally and exteriorly of the lever side for rocking cooperation with a coacting V-bearing and having at the side thereof a round trunnion rotatively adjustably seated in said hole, said trunnion having a peripheral groove, a member adjustable along said bore and provided with a wedge end facing the trunnion groove, and a round element rotatably interposed between the sides of the trunnion groove, the wall of the bore, and the wedge end and upon adjustment of said member along the bore forced by the wedge end towards and into wedging locking engagement with the wall of the bore and the sides of the trunnion groove to thereby fix the knife edge against rotative movement relative to the lever and to locate and fix the longitudinal position of the knife edge. 145
